SMOKING STAND

Jesse A. Carpenter, Duncan, Okla.

Application April 13, 1954, Serial No. 29,974

Term of patent 14 years

(Cl. D85—2)

Fig. 1

To all whom it may concern:

Be it known that I, Jesse A. Carpenter, a citizen of the United States, residing at Duncan, in the county of Stephens and State of Oklahoma, have invented a new, original, and ornamental Design for a Smoking Stand, of which the following is a specification, reference being had to the accompanying drawing, forming part thereof.

Fig. 1 is a perspective view of a smoking stand, showing my new design, and

Fig. 2 is a top plan view thereof.

I claim:

The ornamental design for a smoking stand, as shown.
